(57) **CLAIM**

I claim the ornamental design for a periscope toy, as shown and described.

DESCRIPTION

FIG. 1 is an enlarged rear-side perspective view, taken from the left side, of a periscope toy embodying the present invention.

FIG. 2 is a rear-side perspective view taken from the right side of the periscope toy.

FIG. 3 is a front-side perspective view taken from the left side of the periscope toy.

FIG. 4 is a left-side view of the periscope toy.

FIG. 5 is a right-side view of the periscope toy.

FIG. 6 is a rear view of the periscope toy.

FIG. 7 is a front view of the periscope toy.

FIG. 8 is an enlarged top view of the periscope toy; and,

FIG. 9 is an enlarged bottom view of the periscope toy. The portions of the periscope toy shown in broken lines are for illustrative purposes only and form no part of the claimed design.
